C. Badgerman & J. Green.

Mortising Machine.

PATENTED

JAN 21 1868

73428

United States Patent Office.

CORNELIUS BAGGERMAN AND JOHN GREEN, OF ST. LOUIS, MISSOURI.

Letters Patent No. 73,428, dated January 21, 1868.

IMPROVEMENT IN MORTISING-MACHINES.

The Schedule referred to in these Letters Patent and making part of the same.

TO ALL WHOM IT MAY CONCERN:

Be it known that we, CORNELIUS BAGGERMAN and JOHN GREEN, of St. Louis, in the county of St. Louis, and State of Missouri, have invented a new and useful Improvement in Franking-Machines for Mortising Sash-Rails; and we do hereby declare that the following is a full and clear description thereof, reference being had to the accompanying drawings, and to the letters of reference marked thereon.

This invention relates to an improved arrangement of the chisels, whereby they are enabled to cut from both sides of the piece to be mortised at one operation, the chisels being operated by cam-gearing, and the piece to be mortised held in position on an adjustable table by means of sliding holders, also operated by cam-gearing.

To enable those skilled in the art to make and use our improved machine, we will proceed to describe its construction and operation.

Figure 1 of the drawings is a plan of the machine.

Figure 2 is a side elevation of it, and

Figure 3 is a longitudinal sectional elevation.

A is the framework of the machine, on one end of which is placed the driving-shaft A¹, and on the other end the sliding arbor-frame A², the latter frame having an adjustable connection with the former by means of the set-screws a, in such a manner that it may be set so as to accommodate different widths of stuff. The table B, on which the piece B' is placed to be mortised, is adjustable as to height, by means of the set-screws b, so as to accommodate the different thicknesses required, the said screws working in slots in the table B for that purpose. In order to allow a longitudinal adjustment of the table, a series of holes, b', is made in the side of the frame A, to which the said screws b may be changed when required. There are two chisel-arbors, C and C', the former of which has its bearings in the frame A², and the other in the frame A. Both of the chisel-arbors are actuated in harmony with each other by the cam-wheel D, the cam-rods d operating the arbor C', and connecting-rods d¹ transmitting motion from the rods d to the arbor C. As it is necessary to adjust the frame A² and its arbor C, at different distances, forward and backward, to accommodate different thicknesses of stuff for the piece B', the attachment of the arbor C to the rods d¹ must also be adjustable, and this is most readily done by means of the nuts d² d³, which may be used to move the arbor-arms d⁴ backward or forward, as may be required. The cam-wheel D has a double-flanged rim, which passes between the sheaves d⁵ d⁶, attached to the cam-rods d, and thereby forces the said rods forward or backward by means of the internal cam d⁷, or the external cam d⁸, the motion given by the cam d⁷ being just sufficient to draw the chisel c of the arbor C into the piece B' a short distance, and then the cam, d⁸, is of such size, and so located on the rim of D, as to force the chisel c', of the arbor C', the remaining distance desired into the opposite side of the piece B', and thus a completely-formed mortise, cut from both sides of the piece, is finished at each revolution of the machine. The formation, size, and location of the cams d⁷ d⁸, upon the rim D, are such that a short, quick, reciprocating motion is given to the chisels c c', and then the said chisels are allowed to remain stationary a sufficient length of time for the removal of the piece B', and the substitution, instead thereof, of a new piece, the stationary time being occupied by the revolution of the circular part of the rim d⁹. There are two sliding-holders E, operated by the cams E', located upon the shaft A, in much the same manner as are the cam-rods d. The construction of the cams E' and the rods E is such that ends, e e, of said rods will be forced hard against the piece B', just an instant before either chisel strikes it, and hold the said piece up hard against its table until after the last chisel shall have left it.

Having described our invention, what we claim, is—

The combination of the sliding chisel-arbors C C', the sliding-holders E, the cam-rods d, the connecting-rods d¹, the cam-wheel D, and the cams E', constructed and operating substantially as described.

In testimony of which invention, we hereunto set our hands, in the presence of—

CORNELIUS BAGGERMAN,
JOHN GREEN.
